UNITED STATES PATENT OFFICE.

JAMES E. WILLIAMS, OF ST. LOUIS, MISSOURI, ASSIGNOR TO LINTON WILLIAMS, OF ATHENS, WISCONSIN.

SEAL.

SPECIFICATION forming part of Letters Patent No. 552,566, dated January 7, 1896.

Application filed June 10, 1895. Serial No. 552,242. (No model.)

To all whom it may concern.

Be it known that I, JAMES E. WILLIAMS, a citizen of the United States, and a resident of St. Louis, in the State of Missouri, have 5 invented certain new and useful Improvements in Seals; and I do hereby declare that the following is a full, clear, and exact description thereof.

My invention has for its object to provide 10 a simple, economical seal that may be secured in place without the use of a seal-press and which cannot be opened without it being apparent at a glance that such an operation has taken place.

15 A further object of my invention is to facilitate the keeping of seal-records by train-conductors and others.

The several objects above enumerated I attain by the construction and combination 20 of parts hereinafter set forth with reference to the accompanying drawings and subsequently claimed.

In the drawings, Figure 1 represents an elevation of a seal constructed according to my 25 invention, the view being partly in section on line 1 1 of Fig. 2; Fig. 2, a plan view partly in horizontal section on line 2 2 of Fig. 1; Fig. 3, a detail elevation of one extremity of the shackle, and Fig. 4 a like view showing 30 the seal in position.

Referring by letter to the drawings, A represents my shackle, herein shown as made 35 from a strip of sheet metal bent to form a circular band having quarter-twist extremities that are lapped on each other after said shackle is run through a hasp, staple or eyelet.

While I have shown a single-piece sheet-metal shackle it is practical to utilize other material, and it is also practical to joint said 40 shackle as well as to vary its shape without departure from my invention.

In any of the various possible forms of the shackle I provide for an engagement of its extremities, and as a preferable construction 45 I show the extremity b having a spring-tongue c struck out from the metal, the other extremity d being formed with a slot e for the engagement of said tongue, but where material other than sheet-metal is employed in the

manufacture of the shackle it may be necessary to slightly change the detail concerning the aforesaid tongue and catch for the same. 50

The sleeve B for the shackle is in the form of a tube made from lead or other suitable material in such shape as may be found necessary or desirable. 55

In practice the sleeve is slipped onto one extremity of the shackle and the other extremity is pressed into said sleeve to effect a catch of the spring-tongue, after which it is impossible to open said shackle without splitting the aforesaid sleeve, the latter being secured against endwise displacement at the time the engagement takes place, because of the quarter-twist of each shackle extremity. 60 It is also intended to have the sleeves cast with characters designating stations from which they issue, and thus train-conductors and others can always obtain the proper data for their records, a matter that is sometimes difficult or impossible with the ordinary seals carelessly set by a seal-press. 65

My seal is especially designed for freight-cars, but it is also applicable for use in connection with mail and express receptacles. 70

Having thus described my invention, what I claim as new, and desire to secure by Letters Patent, is—

In a seal a shackle, having its extremities one-quarter twist from the remainder thereof, 80 a tongue struck up from one of said extremities, and the other of the same provided with a slot, in combination with a sleeve in the form of a tube that being placed on one of the shackle-extremities receives the other and 85 prevents disengagement of the automatically-interlocked tongue and slot, said tube being of itself held against longitudinal displacement by the quarter-twists of the shackle.

In testimony that I claim the foregoing I have hereunto set my hand, at St. Louis, in the State of Missouri, in the presence of two witnesses. 90

JAMES E. WILLIAMS.
